UNITED STATES PATENT OFFICE.

JAMES F. McELROY, OF ALBANY, NEW YORK; SUSIE H. McELROY, EXECUTRIX OF SAID JAMES F. McELROY, DECEASED, ASSIGNOR TO CONSOLIDATED CAR-HEATING COMPANY, A CORPORATION OF WEST VIRGINIA.

ELECTRIC SWITCH.

1,198,736.

Specification of Letters Patent. Patented Sept. 19, 1916.

Application filed August 11, 1911. Serial No. 643,577.

To all whom it may concern:

Be it known that I, JAMES F. McELROY, a citizen of the United States, residing at Albany, county of Albany, State of New York, have invented certain new and useful Improvements in Electric Switches, the following being a full, clear, and exact disclosure of the one form of my invention which I at present deem preferable.

10 For a detailed description of the present form of my invention, reference may be had to the following specification and to the accompanying drawing, which illustrate my invention.

15 Figure 1 shows a top view of my switch, Fig. 2 a front elevation thereof, and Fig. 3 a side elevation thereof, the surrounding box or casing being shown in section in each figure. Fig. 4 is a perspective view illustrating the switch arm and plate disconnected.

20 My invention consists in a simple form of electric switch composed essentially of two castings and a spring, one casting being a stationary and the other a movable part of 25 the switch, while the spring serves to hold the two parts together in working relation without resort to the pivoting of one part upon another by means of a pivot-pin or spindle, as in the usual arrangement. I have 30 also shown my switch, for purposes of illustration, as of the type designed for temporary closure of the circuit by moving the handle to either side and holding it there during the closure of the circuit. The 35 spring being so arranged as to bring the switch arm back to its central position when released by the operator.

35 Turning to the drawings, C represents the usual insulating base upon which is seated a 40 flat plate or casting B provided with two projections D¹ and D². The switch-arm is shown at A and is provided at one end with a handle A¹ and at its opposite end (as clearly appears in Fig. 3) is turned inward 45 and terminates in a short plate A² lying in a plane parallel to the length of the arm A. The said plate A² (as clearly appears in Fig. 2) is somewhat wider than the switch-arm A and is seated between the two projections D¹ D². The two upper corners of 50 the plate A² are curved outwardly and provided with undercut portions so as to hook over the said projections, while below the projections the outer edges of the plate are

curved each on the arc of a circle struck 55 from the axis of the opposite projection as a center. Thus the curved edge d² is centered around the axis of the projection D¹, and, similarly, the curved edge d¹ is centered around the axis of the projection D². The 60 spring S is secured at its upper end to the under side of the switch arm A, being hooked into a flange in the corner produced by the bend at the upper end of the switch arm, while at its lower end the spring is 65 secured to a lug c on the front face of the base plate B. The spring thus exerts its contractile force in the general direction of the switch-arm A to hold the plate A² upon its seat on the lugs D¹ D², while it also draws 70 the switch arm inwardly toward the base plate B, thereby bringing a locking lug a on the under side of the switch-arm into engagement with the locking portion b with which base plate B is provided to lock the 75 switch-arm in its central position.

Assuming the parts to be of the shape and relative disposition above described, it will be manifest that the switch may be operated by first moving the handle A¹ away from 80 base B to release it, and then turning it to the right or left to close the circuit on one side or the other. If the handle A¹ is turned to the right, the switch arm will rotate around the lug D¹, while the curved guiding 85 surface d² will pass along the opposite projection D². A stop screw B¹ serves to limit the extent of movement of the plate A². If the handle A¹ is moved to the left, the arm will turn around the projection D² and the 90 curved guiding edge d¹ will pass along the opposite projection D¹. The spring S acts eccentrically to both of the projections and will, therefore, tend to oppose the movement of the switch-arm from its central position, 95 and when the switch-arm is released, will tend to restore it to the said central position. That is to say, the spring S acts centrally between the projections D¹ and D² and therefore acts eccentrically to both of them. The 100 space underneath the top flange of the undercut projections D¹ and D² will be such as to permit of the slight locking and unlocking movement of the switch-arm toward or away from the base plate B.

105 The construction described above is an extremely simple one, the switch arm and its plate A² being formed as a single casting,

while the stationary part, including the base plate B and the projections D¹ and D² may also be formed as a single casting, or the projections may be riveted thereto as indicated in the drawing. To assemble these two castings in their working relation to each other it is only necessary to place the switch-arm in its normal seating position and in engagement with the projections. This eliminates the usual pivoting of the movable part on the stationary one, while the two parts are readily separable for inspection or replacement.

What I claim as new and desire to secure by Letters Patent is:

1. An electric switch comprising a stationary base provided with spaced apart fulcrum members and spaced apart contacts, a switch arm mounted between said contacts and normally out of engagement with both, said switch arm being movable toward either contact upon the respective fulcrum members, means for preventing movement of the switch arm toward either contact without first moving said arm away from said base, and a spring for yieldingly holding said switch arm against movement.

2. An electric switch comprising a stationary base provided with spaced apart fulcrum members and spaced apart contacts, a switch arm mounted between said contacts and normally out of engagement with both, said switch arm being movable toward either contact upon the respective fulcrum members, said switch arm having a portion extending between the fulcrum members shaped to be guided by either member when the other is acting as a fulcrum, means for preventing movement of the switch arm toward either contact without first moving said arm away from said base, and a spring for yieldingly holding said switch arm against movement.

3. An electric switch comprising a stationary base provided with spaced apart contacts, and spaced apart fulcrum members, a switch arm located between said contacts and normally out of engagement with

both, said switch arm having seats for engaging the fulcrum members, said switch arm being movable toward either contact and having the portion between the fulcrum members shaped to be guided by either member when the other serves as a fulcrum, means for preventing movement of the switch arm toward either contact without first moving said arm away from said base, and a spring for yieldingly holding said switch arm against movement.

4. An electric switch comprising a base having spaced apart projections, a switch arm provided with spaced apart guides to engage said projections, the curve of each guide being centered from a projection on the opposite side of the stationary part, said members serving as fulcrums for said arm, and a spring acting to hold the parts in engagement longitudinally, and means for normally preventing lateral movement of said arm.

5. An electric switch comprising a base provided with spaced apart fulcrums, a switch arm mounted between and coöperating with both fulcrums, said arm being provided with guides coöperating with either fulcrum when the arm swings on the other fulcrum, and a spring acting to press the switch arm into seating engagement with both projections, and also to hold the same in engagement with said base.

6. In an electric switch, a stationary base having projections, a switch-arm having seating engagement at one end with the projections of said stationary base, and also a locking engagement with said base, and a spring acting upon said switch arm to maintain both the locking and seating engagement.

In witness whereof I have hereunto set my hand, before two subscribing witnesses, this 9th day of August, 1911.

JAMES F. McELROY.
